UNITED STATES PATENT OFFICE.

JOHN SCHREINER, OF CHICAGO, ILLINOIS, ASSIGNOR TO PAUL W. KOCH & COMPANY, OF CHICAGO, ILLINOIS, A CORPORATION OF ILLINOIS.

SAW.

Application filed December 21, 1925. Serial No. 76,623.

My invention relates to sawing mechanism and more particularly to an improved saw having a plurality of blades for forming a plurality of slits at one time.

5 In the laying of electrical conduit across wooden joists, beams and other analogous members, I find it highly desirable to form pockets or notches in the aforesaid wooden members for receiving the conduit by first 10 cutting a plurality of parallel slits therein and then knocking out the material intermediate the slits.

In order to accomplish this both expeditiously and efficiently, I have invented and 15 designed a saw for simultaneously cutting a plurality of slits. My saw includes briefly a plurality of spaced saw blades and means for varying the space separating the blades.

The object therefore of the present invention is to provide an improved saw for 20 cutting a plurality of spaced slits contemporaneously.

In the accompanying drawing,

25 Figure 1 is a plan view of my novel saw; Figure 2 is a side view of the saw structure illustrated in Figure 1;

30 Figure 3 is an enlarged sectional view taken on the line 3—3 of Figure 2 looking in the direction indicated by the arrows and illustrating how the saw is used;

Figure 4 is a sectional view taken on the line 4—4 of Figure 2 and enlarged like Figure 3, and

35 Figure 5 is an enlarged sectional view similar to Figure 3 but differing therefrom in that it illustrates the strengthening rib in a different position so as to increase the space separating the blades.

Referring now to the drawing in detail 40 in which like reference numerals designate similar parts throughout the several views, 10 denotes a handle and 11 a holding device or guiding knob. The handle 10 is somewhat analogous to the handle employed on the usual plane and the knob 11 is also 45 similar to the guiding knob used on such planes.

Associated with the handle 10 and the 50 knob 11 are a pair of saw blades 12 and 13 which, as I have illustrated in Figure 3, are each preferably made two inches in width. In fact, the section illustrated in Figure 3 is actually drawn to full scale. The blades 12 and 13 are spaced at one end by the lower 55 portion 14 of the knob 11 and at the other

end are spaced by the lower portion 15 of the handle 10. The portions 14 and 15 enable the blades 12 and 13 to be maintained in a parallel relationship.

In Figure 3, I have illustrated the blades 60 12 and 13 in conjunction with a wooden or beam member 16, which is being slit thereby. Inasmuch as the ordinary type of standard conduit has an outside diameter of seven-eighths of an inch, I find it desirable 65 to cut an aperture in the beam 16 approximately an inch in width and therefore space the blades 12 and 13 accordingly. The portion 17 of the wooden member 16 intermediate the blades 12 and 13, as well as the 70 slits formed in the member by the blades 12 and 13, is adapted to be knocked out by any suitable means such, for example, as a chisel.

In order to give the blades the necessary 75 rigidity, I provide the top edge of each of the blades with a U-shaped rib 20 which may be pressed thereon in any desirable manner. The ribs 20 are mounted upon the blades 12 and 13 in much the same manner 80 as the ribs are mounted on the saw blades of the so-called backed saws. These ribs not only afford a means of strengthening or giving the necessary rigidity to the blade, but also limit the depth that the blade may penetrate into any member which it is desired 85 to slit. The ends of each rib 20 are cut in such a manner as to enable the saw blades 12 and 13 to engage the portions 14 and 15. As clearly shown in Figure 1, a portion 21 90 of each rib is cut away in order to form a shoulder 22. This enables the portion 14 of the knob 11 to abut the shoulders 22 at one end and to abut the blades 12 and 13 at its side. The portion 14 is thus enabled 95 to cooperate with the ribs 20 through the shoulders 22 thereof to prevent undue strains and stresses from being imposed on the saw blades 12 and 13. A bolt 23 extends through one of the ribs 20, the blade 12, the portion 14 of the guiding knob 11 and is threaded at 24 (Fig. 3), into both the blade 13 and the associated ribs 20. Another bolt 23' extends through the portion 14 of the knob 11 in the same manner as the bolt 23. 100

The other ends of the aforesaid ribs are cut in a similar manner to the previously described ends to form shoulders 22' which abut the portion 15 of the handle 10. The ends of the blades 12 and 13 are fastened 110

to the portion 15 by bolts 23" in the same manner as the other ends are fastened to the portion 14 by the bolts 23 and 23'.

Now it is evident that the blades 12 and 13 are illustrated in Fig. 3 as being spaced a distance apart sufficient to enable them to cut a pair of slits in the member 16 approximately an inch apart. Also, it is obvious that the depth of the slits will be limited by the edges of the ribs 20. After the slits have been completed a portion 17 intermediate them is knocked out or removed by means of a chisel leaving a pocket in which a conduit having an outside diameter of seven-eighths of an inch may be laid.

In practice, approximately ninety per cent of the conduits used in buildings and other analogous structures are of the size above mentioned. The other ten per cent of the conduits used is usually somewhat larger having an outside diameter of one and one-eighth inches. In order to enable my blades 12 and 13 to cut a pair of slits spaced further apart than those illustrated in Fig. 3 so as to enable the forming of a pocket to accommodate the one and one-eighth inch conduit, I provide means whereby the blades 12 and 13 may be easily removed from the holding members 10 and 11 and reversed in position so that the distance between the blades is greater as is illustrated in Fig. 5.

In Fig. 5, the blades are shown spaced apart from each other a distance of about one and one-quarter inches. Obviously, after the slits have been formed in the beam or joint member and the intermediate portion knocked out, an aperture or pocket will remain adequate to receive the larger size of conduit. In order to space the blades 12 and 13 in this manner, all that is necessary to be done is to remove the blades from the holding devices 10 and 11 by removing the bolts associated therewith. Then the position of the blades with respect to the holding members is reversed, so that instead of the surface of each blade being flushed with the portions 14 and 15, the ribs are flushed therewith. This will result in the shoulders 22 and 22' being on the outside of the tool. I have indicated the portions of the ribs 20 abutting the portion 14 of the knob 11 in Figure 5 by the reference numeral 26. The bolts are then inserted in the parts of the device and the blades 12 and 13 secured to the members 10 and 11.

In addition to varying the spacing of the saw blades 12 and 13, it is possible to vary

the depth of the slits formed by these blades by varying the width of the ribs 20. That is to say, by increasing or decreasing the legs of the U-shaped ribs 20, the distance that the saw blades may penetrate the member 16 may be varied. Then too, since the blades are very easily detached from the holding devices 11 and 10, they may be replaced by new blades when worn out or by different size blades whenever the occasion may demand the same. Thus, it will be seen that I have provided a rigid tool or saw, the parts of which may be easily replaced or changed. The saw is one that is very economical to manufacture as well as one which will hold up for a considerable period of time in practice.

I desire it understood that although I have illustrated and described the preferred embodiment of my invention that the invention is not to be limited thereby, but only in so far as defined by the scope and spirit of the claims hereto appended.

I claim:

1. In a tool of the class described, a pair of parallel saw blades, a pair of elements for spacing the blades a given distance apart, one of said elements having associated therewith a handle, means for fastening the blades to the elements, and a rib associated with an edge of each of the blades for preventing flexing of the blades and for serving to limit the depth of the cut by the said blades, each of said ribs being formed in such a manner that by reversing said blades the distance separating the blades may be varied.

2. In a tool of the class described, a pair of parallel saw blades, a pair of elements for spacing the blades a given distance apart, means for fastening the blades to the elements, said elements comprising means adapted to be gripped manually to actuate the saw blades, and a rib associated with an edge of each of the blades, each of said ribs having each end provided with a cut away portion to permit of the corresponding spacing element to abut the side of the associated blade, said blades being reversible to vary the distance separating them, said ribs being adapted to be used to increase the said distance when said blades are reversed.

In witness whereof, I hereunto subscribe my name this 17th day of December, 1925.

JOHN SCHREINER.
